UNITED STATES PATENT OFFICE.

ALFRED M. JONES, OF DES MOINES, IOWA, ASSIGNOR TO HOBERT R. JONES, OF COLUMBUS, OHIO.

SURGICAL APPLIANCE.

1,215,028.

Specification of Letters Patent.

Patented Feb. 6, 1917.

Application filed November 2, 1915. Serial No. 59,184.

To all whom it may concern:

Be it known that I, ALFRED M. JONES, a citizen of the United States, residing at Des Moines, in the county of Polk, State of Iowa, have invented certain new and useful Improvements in Surgical Appliances; and I do hereby declare the following to be a full, clear, and exact description of the invention, such as will enable others skilled in the art to which it appertains to make and use the same.

This invention relates to improvements in surgical appliances and particularly to appliances for use in treating patients in hospitals, sanatoriums, and the like.

The principal object of the invention is to provide an appliance which is intended to treat patients for the purpose of protecting them from practising masturbation or self-abuse.

Another object is to provide a restraining device of this character which will protect the patient from self-abuse, and at the same time permit the patient freedom of urination and evacuation.

Other objects and advantages will be apparent from the following description when taken in connection with the accompanying drawing.

30 In the drawing:

Figure 1 is a front elevation of the appliance.

Fig. 2 is a rear elevation of the appliance.

Fig. 3 is a vertical sectional view on the line 3—3 of Fig. 1.

Fig. 4 is a horizontal sectional view on the line 4—4 of Fig. 2.

Fig. 5 is a front elevation of the appliance worn by a female.

Fig. 6 is a vertical sectional view on the line 6—6 of Fig. 5; and

Fig. 7 is a vertical sectional view of a portion of a modified form of garment for a female.

45 Referring particularly to the accompanying drawings, 10 represents a bifurcated nether garment which is formed of any suitable strong material, such as canvas, leather or the like. The rear of the garment is split vertically, as at 11 to permit of evacuation by the patient. The garment is provided with a belt 12, to which are secured the suspenders 13 engaging over the shoulders of the patient, and provided with a breast strap 14 and a back strap 15 to pre-

vent the patient from pushing the suspenders down from the shoulders. In the seams of the belt are sewed the chain 12'. Additional loose straps 16 depend from the shoulders of the suspenders, and have on their lower ends the wrist straps or cuffs 17 for restraining the patient's hands. An enlarged opening 18 is formed in the front of the garment, and over this opening is removably secured a patch formed of canvas or leather, as shown at 19, this patch being reinforced by a flexible wire screen 20. In the patch is formed an opening 21, and permanently secured over this opening is a soft rubber pouch 22, which depends in the front of the garment and is adapted to contain the penis and testicles of the male. This pouch may be reinforced with wire mesh, if desired. Above the patch is secured a flap 23, which is adapted to be lowered in position to cover the rubber pouch, but may be easily and quickly raised when the patch is to be removed for cleaning purposes. This flap also protects the rubber pouch from wear by frictional contact with the outside clothing. The overlapping edges of the rear split of the garment are reinforced with wire 24, and prevents the patient from getting his or her hand into the garment. The belt of the garment is open at one side, as at 25, and is provided with a lock 26, thus preventing any possibility of removal of the garment by the patient.

The end of the rubber pouch is provided with a stiff ring 27 which produces an opening 28 through which urine is discharged. This ring is of such diameter that the patient cannot get his or her finger therein.

In the device used on females, the construction is practically the same as that just described for the males, except that the rubber pouch 22' is not quite so deep, and is considerably wider, serving as a bag to receive urine. If desired, this rubber pouch may be dispensed with and an open wire mesh pouch substituted through which the urine can pass, as shown at 31 in Fig. 7.

The lower ends of the legs 29 of the garment are provided with comparatively tight bands 30, the same being tight enough to prevent the entrance of the hand by the patient, while at the same time loose enough for the comfort of the wearer. In the seam of the band is sewed a chain 30'.

The garment and the suspender straps are

reinforced with woven wire fabric 32. This reinforcement insures against the possibility of the patient forcing an opening through which to insert the hand.

5. What is claimed is:

1. A surgical appliance comprising a bifurcated nether garment formed of flexible wire screen covered with canvas, suspenders for the suspension of the garment, the rear 10 of the garment being split vertically and having reinforcements in the edges thereof, a removable flexible pouch carried at the front of the garment, and a movable flap secured to the garment above the pouch and depending thereover to protect the pouch from the rubbing wear of the outer garments of the wearer.
- 15 2. A surgical appliance comprising a bi-

furcated nether garment, means for suspending the same on the patient, a removable member on the front of the garment, a soft rubber pouch carried by the removable member, restraining device for the hands of the patient carried by the suspending means, non-elastic bands on the lower ends of the 25 legs of the garment, a reinforced protective closure in the rear of the garment, and a non-elastic belt on the upper end of the garment.

In testimony whereof, I affix my signature, in the presence of two witnesses.

ALFRED M. JONES.
